UNITED STATES PATENT OFFICE

153,731

DESIGN FOR A SKI BOOT

Rudolf Rominger, St. Moritz, Switzerland

Application August 6, 1947, Serial No. 140,722
In Switzerland June 2, 1945

Term of patent 14 years

(Cl. D7—7)

To all whom it may concern:

Be it known that I, Rudolf Rominger, a citizen of the Swiss Confederation, residing in St. Moritz, Canton of Graubünden, Switzerland, have invented a new, original, and ornamental Design for a Ski Boot, of which the following is a specification, reference being had to the accompanying drawing, forming part thereof, in which

Fig. 1 is a perspective view of a ski boot embodying my new design;

Fig. 2 is a left-hand side elevational view thereof;

Fig. 3 is a right-hand side elevational view thereof; and

Fig. 4 is a rear view thereof.

Fig. 5 is a front fragmentary view, illustrating the inside.

I claim:

The ornamental design for a ski boot, substantially as shown.

RUDOLF ROMINGER.
